DESIGN FOR A REMOTE-CONTROLLER CASING

Walter Lockwood Martling, Jr., Chicago, Ill., assignor to Mills Industries, Incorporated, Chicago, Ill., a corporation of Illinois

Application May 16, 1946, Serial No. 129,748

Term of patent 3½ years

(Cl. D26—14)

To all whom it may concern:

Be it known that I, Walter Lockwood Martling, Jr., a citizen of the United States of America, residing at 196 East Delaware, Chicago, in the county of Cook and State of Illinois, have invented a new, original, and ornamental Design for a Remote Controller Casing, of which the following is a specification, reference being had to the accompanying drawing, forming part thereof.

Fig. 1 is a front elevational view of a remote controller casing showing my new design;

Fig. 2 is a side elevational view thereof;

Fig. 3 is a rear elevational view thereof; and

Fig. 4 is a top plan view.

I claim:

The ornamental design for a remote controller casing, as shown.
